(57) **CLAIM**

The ornamental design for a manifold sprayer, as shown and described.

DESCRIPTION

FIG. 1 is a perspective front view of a manifold sprayer, shown in operation in a container while connected to a water delivery system;

FIG. 2 is a front elevation view of the manifold sprayer, rear elevation view is an identical image thereof;

FIG. 3 is a left side elevation view of the manifold sprayer, right side elevation view is an identical image thereof;

FIG. 4 is a top plan view of the manifold sprayer; and,

FIG. 5 is a bottom plan view of the manifold sprayer.

The container, water delivery system, spraying and plant clip-
pings are shown in broken lines for illustrative purposes only
and form no part of the claimed design.
